UNITED STATES PATENT OFFICE.

ROBERT W. RAINES, OF MEMPHIS, TENNESSEE, ASSIGNOR OF ONE-THIRD TO GERSON SCHARFF AND ONE-SIXTH TO ELMO S. BOYTE, BOTH OF MEMPHIS, TENNESSEE.

RAIL-JOINT.

1,278,504

Specification of Letters Patent. Patented Sept. 10, 1918.

Application filed October 11, 1916. Serial No. 125,067.

To all whom it may concern:

Be it known that I, ROBERT W. RAINES, a citizen of the United States, residing at Memphis, Shelby county, and State of Tennessee, have invented and discovered certain new and useful Improvements in Rail-Joints, of which the following is a specification.

The present invention relates to new and useful improvements in rail-joints and consists in the combinations and arrangements of elements hereinafter described and particularly set forth in the accompanying claims.

15 The invention has for its purpose to provide a rail-joint which will avoid the use of the fish-bar plate usually employed, and wherein the ends of the rails are designed to interlock and overlap to overcome the beating down of the rail ends and thereby prevent the incident jarring of the car wheels passing thereover.

20 The invention has for its further purpose to provide a rail-joint with the connecting ends thereof constructed to strengthen the track at the joint, and to allow the rails to freely expand and contract; and in which the joint members may be readily formed in the making of the rail without requiring any appreciable departure from the present 25 steps of manufacture.

The invention is shown by way of illustration in the accompanying drawings, wherein,

30 Figure 1 is a perspective view of the rail-joint,
Fig. 2 a horizontal sectional view thereof,
Fig. 3 a transverse sectional view, and,
Fig. 4 is a perspective view showing the 35 joint members dis-assembled.

Referring to the construction in further detail, 5 designates the rail end which is constructed with an enlarged web portion 6, as clearly shown in Figs. 1 and 2; and said 40 web portion is cut-away on one side to provide a tongue 7, and form a recess or chamber 8 that receives the projecting tongue portion 9 of the connected rail.

The tongues 7 and their complementary

fitting recesses 8 are designed preferably 50 rectangular, and said recesses have squared ends 10 and ledges 11 forming abutting surfaces for the tongues fitting therein, as shown in Figs. 1 and 4. This interlocking engagement between the rail tongues and recesses forms a strong support for the track at the rail-joint.

The rail tread and base are cut diagonally between the end of the tongue and the recess as indicated at 12, which thereby gives 60 a union between the rails that is smooth and continuous for the wheels passing thereover, and also prevents jarring and beating down of the rail ends. This condition of the rails, as is well known, is a cause of great financial 65 loss to railroads, and requires the maintenance of a large force to keep the tracks in repair.

70 The manner of securing the rail-joint consists of bolts 13, or other suitable devices, that pass through slotted apertures 14 and 15 formed in the tongue of each rail, at the projecting portion 9, and recess 10 thereof, respectively. Said bolts secure the joint members after the usual manner and by 75 reason of the slots 14 and 15, and the rails are permitted to expand or contract in the usual way. There is a sufficient space or clearance 16 between the tongue part 9 and the wall 10, to take up this relative movement between the rails, as will be understood.

It is obvious that those skilled in the art may vary the details of construction and arrangement of parts without departing 80 from the spirit of my invention, and therefore I do not wish to be limited to such features except as may be required by the claim.

Having thus fully described my invention, what I claim as new and desire to secure by Letters Patent, is:

90 In a rail joint, the combination of rails having thickened web portions adjacent their adjoining ends, each thickened portion being oppositely recessed to interlock with 95 their contacting faces disposed in alignment with the medial vertical plane of the rail tread, the base and tread portions of the

5 rail being formed with diagonal contacting edges, and said base portions being integral with and extending beyond the extremities of said web portions, substantially as set forth.

In witness whereof I have hereunto set my hand and seal at Memphis, Tenn., this

27th day of September, A. D. nineteen hundred and sixteen.

ROBERT W. RAINY. [L.S.]

Witnesses:

JNO. W. SPENCE,
C. S. PARKER.
